(57) CLAIM

The ornamental design for a battery for a hair clipper, as shown and described.

DESCRIPTION

FIG. 1 is a perspective view of a battery for a hair clipper showing a new design;

FIG. 2 is a left side elevational view thereof, the right side being a mirror image;

FIG. 3 is a front elevational view thereof, the rear being a mirror image;

FIG. 4 is a top plan view thereof;

FIG. 5 is a bottom plan view thereof; and,

FIG. 6 is another perspective view thereof.

The broken lines are for illustrative purposes only and form no part of the claimed design.
